UNITED STATES PATENT OFFICE.

ALVIN M. THREEWITS, OF CENTERVILLE, INDIANA.

RAILROAD-TIE AND RAIL-LOCK.

1,157,459.

Specification of Letters Patent.

Patented Oct. 19, 1915.

Application filed December 3, 1913. Serial No. 804,486.

To all whom it may concern:

Be it known that I, ALVIN M. THREEWITS, a citizen of the United States, residing at Centerville, in the county of Wayne and 5 State of Indiana, have invented new and useful Improvements in Railroad-Ties and Rail-Locks, of which the following is a specification.

This invention relates to railroad ties and 10 rail locks, and the primary objects of the invention are to provide a simple, economical, reliable, durable, convenient, anti-creeping, all metal railroad tie which will afford the necessary cushion to the rails and to the 15 rolling stock, etc., the said tie being adapted to receive a coating of pitch tar which greatly adds to the life of the tie.

A further object of the invention is to 20 provide a tie and rail lock that combines safety, strength, economy, convenience, simplicity, and efficiency to the highest degree, and which securely guards the rails against being tampered with by malicious persons.

With the above and other objects in view 25 which will appear as the nature of the invention is more fully disclosed the invention resides in the novel construction, combination and arrangement of parts set forth in and falling within the scope of the ap- 30 pended claim.

In the accompanying drawings, Figure 1 is a view of the blank from which the tie is formed. Fig. 2 is a side elevation of the tie. Fig. 3 is a plan view of the same showing 35 the common rail positioned thereon. Fig. 4 is a detail plan view illustrating the wider notched flanged rail secured to the tie. Fig. 5 is a central longitudinal sectional view taken centrally of Fig. 3. Fig. 6 is a detail 40 perspective view looking toward the end of the tie. Fig. 7 is a transverse sectional view taken through the tie. Figs. 8 and 9 are side and end views respectively of the wedge members. Figs. 10, 11 and 12 are front, 45 rear and side views respectively of the clamp member.

The tie contemplated in this invention is all metal and is formed preferably of sheet steel, which is bent to provide a structure 50 which is substantially L-shaped in cross section. The tie thus constructed, comprises

a flat top or body 1, and a single longitudinally extending flange 2, the same being of a length equaling that of the tie along one side or edge thereof, and of a suitable 55 depth to make the tie sufficiently strong, the said tie is adapted to be embedded in the road bed or ballast of the railroad system.

By providing the tie with only a single flange extending along one side of the body, 60 the body of the tie is sustained flexible and resilient to a desired extent and the insertion of the ballasting material beneath the top or body of the tie is not interfered with, thus enabling the tie to be perfectly and 65 practically utilized before and after it has been connected with the rails.

In order to prevent the longitudinal movement of the tie, the latter is provided with flanges 3, at both its ends, which, when 70 the tie is in place are firmly embedded in the road bed. These flanges do not interfere in any way with the insertion of the ballast under the top or body 1 of the tie but assist in retaining the said ballast beneath the tie. 75 By the construction described, a firm and reliable anchorage of the tie in the road and ballast is obtained, preventing both longitudinal and transverse movement of the said tie.

The tie, as heretofore stated, is preferably 80 constructed of a single piece of steel or other malleable material, and the side 2, as well as the end 3 are each formed integrally with the body 1, the side 2 is bent at right-angles 85 to the top or body or upon the score line designated by the numeral 4, and the ends are likewise formed by being bent upon the score lines 5. The flange 2 is formed with a lip 7 as illustrated in the blank shown in 90 Fig. 1 of the drawings and the width of the end members 3 is slightly lesser than the width of the combined top and sides 2, and the end sections 3 are slotted at the juncture of the score lines 4 and 5 to provide an 95 upper tongue 7 for the side 2 and a lower tongue for the end 3. The lip 6 is divided from the lip 7 through the medium of the transverse slit and it will be noted that when the flanges 2 and 3 are bent upon their 100 scores and at right angles to the body 1, the lips 6 and 7 extend at right angles to

each other. The lip 6 is adapted to be bent over the end 3, while the lip 7 is bent over the side 2, and these lips may be riveted together if desired, but from practice it has 5 been found that such a course is not essential.

It will be noted that by constructing the lips as shown and described, the lip 7 will lap around the corner below the lip 6 and 10 hold the side 2, thus effectively holding the sides and ends together.

The top or body 1 is provided adjacent its ends with longitudinally extending, preferably rectangular cutaway portions 8 and 15 9. These cut away portions 8 and 9 are arranged in pairs and each of the said pairs of openings are sufficiently spaced away 20 from each other a little less than the width of the base flanges 10, of the rail 11. By 25 reference to Figs. 1, 3 and 4 of the drawings it will be noted that the rectangular openings 8 and 9 extend a suitable distance beyond the edges of the base flanges 10 of each of the rails 11, and adapted to be inserted 30 within each of the said openings is what I term a clamping member 12. All of the clamping members are of a similar construction, and are, of course adapted to engage each of the edges of the base flanges 10 of 35 the rails. Each of the clamps 12 comprises a central rounded neck portion 13, the same being of a length between the shoulders provided thereby, equaling the thickness of the top or body of the tie. The lower portion of 40 the clamp is formed with diametrically opposite extending fingers 14, which are integrally formed with the neck 13, and the combined length of these fingers is nearly equal to the length of the openings 8 and 9. 45 The thickness of the fingers, as well as that of the neck is nearly equal to the width of the rectangular openings 8 and 9, and the portion of the clamp directly above the neck is formed with an off-set head 15, substantially as shown. The inner face of the head 15 is serrated as at 16, and the said serrations are adapted to engage with similar serrations 17, provided upon the longitudinal edges of the base flanges of the rails, as in 50 the structure illustrated in Fig. 4 of the drawings.

In the remaining figures of the drawings the serrations 16 of the head 15 engage with the smooth edges of the base flanges of the 55 ordinary rails.

In positioning the clamps it is merely necessary to have their fingers arranged longitudinally of the rectangular openings of the tie to insert the said clamps, and by 60 merely turning the same so that its rounded neck will turn in the elongated openings 8 or 9, and the key parts 14 engage with the walls adjacent the openings in the tie will hold the clamp, and the said clamp may be

brought tightly into engagement with the 65 flanges of the rails. In order to secure the clamp in this position I have provided a wedge member 18, this wedge member has its inner face serrated as at 19, and the said serrations are adapted to engage with the 70 outer face or lower back corner of the clamp. The lower outer corner of the clamp is formed with an outwardly projecting tooth 20 (see Fig. 12), the same co-acting with the teeth or serrations 19 of the wedge 18. 75 Again, if desired the wedge 18 may have both of its faces serrated so that the same engaging the outer walls formed by the openings will be effectively prevented from becoming loosened. 80

From the above description, taken in connection with the accompanying drawings, it will be noted that the ties are constructed scientifically and meet every requirement, having every desired feature without weakening the tie. The tie is adapted to be coated with pitch tar which greatly adds to the life thereof. It guards the rails effectively and sustains the same in proper spaced relation with each other. The rail tie lock 90 may be quickly and conveniently positioned upon the tie with the employment of only ordinary tools, such as a hammer or the like. The tie is anti-creeping. The rail clamp lock is also anti-creeping. The tie is 95 easily positioned upon the road bed and effectively holds the ballast solidly under it. The tie is also constructed of a single piece of material without the employment of rivets or other holding devices and the rail 100 clamp can not be removed when once positioned upon the tie without the employment of a special pry bar.

Having thus described the invention what I claim as new, is:—

In combination with a hollow metal tie having its top provided with an elongated opening, of a rail clamp including a web or neck having its opposite sides rounded, a head formed with the neck and extending laterally from the rounded sides thereof, said head having its inner face provided with vertically disposed teeth and being formed with a rail engaging flange which extends the entire length of the head beyond the toothed portion thereof, the neck being of a length approximately equaling the thickness of the top of the tie and having its end opposite that provided with its head formed with lateral fingers extending 110 in the same direction as the head, the said fingers adapted to engage with the underface of the top of the tie when the securing member is passed through the openings and rotated therein and the fingers of the web being formed upon their lower corners diametrically opposite that of the flange of the head with an outwardly projecting lug, a 115 120 125

wedge member having one of its edges provided with transverse teeth throughout, the said wedge member adapted to be passed through the opening of the tie to bind against the end wall thereof and against the outer face of the clamp to have one of its teeth engage with the lug of the said clamp.

In testimony whereof I affix my signature in presence of witnesses.

ALVIN M. THREEWITS.
